DRAFT REGULATOR

Frank J. Jeffries, Akron, Ohio

Application June 11, 1932, Serial No. 616,651

7 Claims. (Cl. 126—286)

This invention relates to draft regulators, and more especially it relates to check drafts such as commonly are used for furnaces using coal or coke as fuel.

5 Furnaces of the character mentioned usually have a draft door in the ash pit, which draft door and the check draft are operated in unison by a remotely positioned control dial, the latter usually being somewhere on the ground floor or 10 upper floor of the building, the furnace being in the basement. This type of furnace requires that the check draft be closed and the draft in the ash pit door or fire pot door be open during firing in order to provide draft for carrying smoke and 15 fumes up the chimney. This position of the drafts is the reverse from that required for maximum heating or complete damping, so that usually it is necessary to adjust the control dial before firing. Frequently this is overlooked and it 20 is then necessary either to return to the upper floor to operate the dial, or to fire the furnace with the drafts improperly set and thereby to permit smoke and fumes to belch from the open fire door and to permeate the entire basement and 25 sometimes the upper floors.

The chief objects of this invention are to provide an improved draft regulator that permits the check draft to be closed independently of the usual control dial; to permit closing of the check 30 draft at the furnace; and to provide such a check draft that may be easily and quickly restored to normal operating arrangement after being closed independently of the usual control mechanism. Further objects include the saving of time and 35 wasted effort in the operation of furnaces; increased convenience; and obviating the smudging of furniture and woodwork by smoke and fumes emitted during the firing of the furnace.

Of the accompanying drawing,

40 Figure 1 is a front elevation of a furnace embodying the improved draft regulator, in its preferred form;

Figure 2 is a vertical section through the improved draft regulator in its normal operating 45 positions; and

Figure 3 is a section similar to Figure 2 showing how the draft regulator operates independently of the normal control mechanism.

Referring to the drawing, 10 is a furnace, 11 is 50 a smoke pipe extending to the usual chimney (not shown), 12 is a flue extending from the top of the fire pot to the smoke pipe 11, and 13 is the usual down draft flue that connects with the flue 12 within the furnace casing and extends to the smoke pipe 11 somewhat below the

flue 12. The furnace is provided with the usual fire door 14 and ash door 15, the latter being formed with an intake draft opening 16 that is controlled by a draft door 17 hinged upon the ash door 15. The flue 12 has the usual damper (not shown) operatively positioned therein, said damper being provided, exteriorly of said flue, with an operating handle 18, and the latter is connected to one end of a chain or other flexible member 19 that extends over suitable sheaves 20, 20 and has its other end provided with a counterweight 21 that is conveniently positioned for manual operation at the front of the furnace. Mounted in the smoke pipe 11 between flues 12, 13 is a check draft pipe 23, and mounted in the 70 latter is the improved draft regulator or check draft, generally designated 25, by means of which air is admitted to the smoke pipe 11 to check the draft through the furnace.

Referring more particularly to Figures 2 and 75 3 of the drawing, the check draft comprises a tubular frame or collar 26 that is removably mounted in the check draft pipe 23 by screws 27, 27 or the like. The outer end of the collar 26 is oblique or inclined as shown, and on the 80 top thereof is formed with a pair of suitable ears, such as the ear 28, that are spaced apart to receive a hinge pin 29. Pivotedly mounted upon the hinge pin 29 are two plates 30, 31 respectively, of which the under plate 30 at least is of 85 the proper size and shape completely to close the oblique opening in the end of the collar 26, thus constituting a draft lid.

Adjacent its free side the draft lid 30 is formed 90 with a slot 33 through which extends an arcuate latch member 34, the latter being pivotally mounted at one end upon a suitable bracket 35 that is mounted upon the under side of the draft lid. The latch 34 also extends through a slot 36 formed in the superposed plate 31, and a latching lug 37 is formed along the lower edge of the slot 36 in position to cooperate with a notch 38 formed in the lower edge of the latch 34 for the purpose of releasably latching together the draft lid 30 and plate 31 so that they may be raised 100 and/or lowered as a unit. A removable stud or pin 39 may be mounted in the free end of the latch 34, and project on both sides of the latter to prevent accidental removal of the latch from the slot 36.

105 Control mechanism for the check draft comprises a remotely located control dial 41 of the usual manually operated type, from which dial extends a chain 42 that is connected to an operating arm 17a on the intake draft door 17, for 110

opening or closing the latter. Another chain 43 extending from the dial 41 is connected to the check draft 25 by means of a bracket 44 mounted upon the plate 31. The arrangement is such that 5 rotation of the control dial 41 concurrently operates the intake draft door 17 and check draft 25, to close one of them and to open the other.

In the operation of the furnace, the proper 10 position of the drafts during firing is that shown in Figure 1 which provides a draft through the furnace to carry off fumes and smoke. However, for maximum heating efficiency the position of the drafts is reversed, the intake draft door being closed and the check draft being in open position 15 as is indicated in broken lines in Figure 2. If the operator forgets to throw the control dial to the position shown in Figure 1, and upon arriving at the furnace finds the check draft open, he has only to lift the latch 34, which releases 20 the notch 38 thereof from engagement with the lug 37, thereby permitting the draft lid 30 to drop to the position shown in Figure 3 to close the check draft. The furnace may then be fired in the usual manner since the opening of 25 the fire pot door 14 will provide the draft necessary to carry the smoke and fumes to the chimney. The draft lid 30 and plate 31 may be latched together again either by raising the draft lid or by turning the control dial to lower the 30 plate 31 to the position shown in full lines in Figure 2.

The invention is of simple construction, easy 35 operation, and is easily mounted in furnaces of standard construction. It makes for cleanly operation and accomplishes the other objects set out in the foregoing statement of objects.

Modification may be resorted to without departing from the spirit of the invention or the scope of the appended claims.

40 What is claimed is:

1. A check draft regulator for furnaces comprising a flue pipe having a check draft opening, a tubular frame having its inner end mounted on the flue pipe and surrounding the opening, a pair of superposed plates hinged to the outer open end of said frame member, at least one of said plates being adapted to close the outer end of said frame member, quickly releasable means for connecting one of said plates to the other whereby the lower 50 plate is supported by the upper plate in the open position of the regulator, and operating means for moving said plates as a unit when so connected.

2. A check draft regulator for furnaces having a flue pipe formed with a check draft opening, said regulator comprising a tubular frame hav-

ing its inner end mounted on the flue pipe and surrounding the opening therein, a pair of superposed plates on the outer open end of said frame member, operating means connected to the uppermost of said plates, and quickly releasable means connecting the lower plate to the upper plate whereby said lower plate is suspended from the upper plate in the open position of the regulator. 80

3. A combination as defined in claim 1 in which the quickly releasable means consists of latching mechanism that operates automatically to connect the plates to each other when said plates are brought together. 85

4. A check draft regulator for furnaces having a flue pipe formed with a check draft opening, said regulator comprising a tubular frame having its inner end mounted on the flue pipe surrounding the opening therein, a pair of hingedly mounted plates on the outer open end of said frame over the opening thereof, quickly releasable latching means operating automatically to connect one of said plates to the other when said plates are brought together, and means for moving said plates as a unit when so latched together to open or close the opening in said frame member. 90

5. A check draft regulator for furnaces having a flue pipe formed with a check draft opening, said regulator comprising a tubular frame having its inner end mounted on the flue pipe surrounding the opening therein, a pair of superposed plates 105 hingedly mounted on the outer open end of said frame member and adapted to move by gravity to cover the opening thereof, operating means connected to the upper plate for raising and lowering the same, and quickly releasable latching 110 means operating automatically to connect the plates to each other when said plates are brought together, so that they may be operated as a unit. 110

6. A check draft regulator for furnaces having a flue pipe formed with a check draft opening, 115 said regulator comprising a tubular frame having its inner end mounted on the flue pipe surrounding said opening, a pair of superposed plates hingedly mounted upon the outer open end of said frame so as to move by gravity to cover the opening thereof, an operating cable connected to the upper plate, and a pivotally mounted latch member on the lower plate that extends through a slot in the upper plate. 120

7. A combination as defined in claim 6 in which the latch member is pivotally mounted upon the under side of the lower plate and extends through a slot in said lower plate. 125
